UNITED STATES PATENT OFFICE.

JOHN H. BRUHN, OF SPIRIT LAKE, IOWA.

THERMOSTAT.

1,206,298.

Specification of Letters Patent. Patented Nov. 28, 1916.

Application filed June 30, 1914. Serial No. 848,191.

To all whom it may concern:

Be it known that I, JOHN H. BRUHN, a citizen of the United States, residing at Spirit Lake, in the county of Dickinson, 5 State of Iowa, have invented certain new and useful Improvements in Thermostats; and I do hereby declare the following to be a full, clear, and exact description of the invention, such as will enable others skilled 10 in the art to which it appertains to make and use the same.

This invention relates to thermostats of the type employing a bar consisting of two differentially expansible materials fixed together as a thermostatic element.

More particularly the invention relates to a bar of this description wherein hard rubber is employed as one of the expansible elements.

20 The principal object of the invention is to provide a novel form of thermostatic bar for use in connection with a thermostat of this description.

With the above and other objects in view 25 the invention consists in general of certain novel details of construction and combination of parts hereinafter fully described, illustrated in the accompanying drawings, and specifically claimed.

30 In the accompanying drawings, like characters of reference indicate like parts in the several views, and Figure 1 is a side elevation of a thermostat having this bar used therein. Fig. 2 is a longitudinal section 35 through a bar constructed in accordance with this invention.

The thermostat used in connection with this invention is properly speaking a two-point thermostatic switch and comprises a 40 base 10 whereon is mounted a J-shaped metallic frame 11. At the end of the stem of this frame is an insulator block 12 upon which is supported one end of a thermostatic element 13 consisting of a pair of bars 45 having different linear coefficients of expansion under the influence of heat, the bars being riveted or otherwise secured together as is common in such devices. It is to be noted that this bar consists of two portions 50 indicated respectively 13^a and 13^b. The portion 13^b is of some suitable metal such as copper or the like and the portion 13^a is of

hard rubber so that when the bar is heated it will respond readily to the expansion and assume a curved position as indicated in 55 dotted lines in Fig. 1.

On the base 10 is a binding post 14 adapted for connection of the line wire as will be hereinafter described and through the base and frame extends a contact member 60 15 which is preferably threaded so that it may be adjusted to suit varying conditions. This contact member is connected to the binding post 14 by means of a wire 16. On the frame 11 is carried an insulator block 65 17 through which passes an adjustable contact member 18, the frame being provided with an opening of said member of sufficient size so that the member 18 does not at any time touch the frame 11, the insulating 70 block preferably being provided with a bushing fitting said opening. These parts are so arranged that under normal heat conditions the thermostatic member 13 will have its free end in contact with the contact member 15 while under conditions of 75 increase of heat this free end will swing over to the member 18 and complete a contact therewith.

It will be observed that the insulation 17 80 is flush with the outer surface of the bar 11 and that on the member 18 is a lock nut 19. By means of this arrangement the lock nut forms a connection between the members 18 and 11 when screwed down so that the 85 device, under these circumstances becomes a two point thermostatic switch. If the lock nut be screwed away from the member 11 then there is no circuit between members 18 and 11 and consequently the device becomes a single point thermostatic switch.

Having thus described the invention, what is claimed as new, is:—

The combination with an insulating base; of a J-shaped conductor plate having its 95 stem secured flat on said base, a contact screw carried by the end of the free arm of the conductor plate and insulated therefrom, a second contact screw extending through the stem of the plate opposite the 100 first screw, and a thermostatic expansion member having one end fixed adjacent the end of the stem of the J-shaped member and its other end located between said screws,

said thermostatic members comprising a strip of insulating material and a strip of conducting material fixed together at one end, the conducting strip being longer than the insulating strip and having its remaining end bent around and clamped to the remaining end of the conducting strip.

Copies of this patent may be obtained for five cents each, by addressing the "Commissioner of Patents, Washington, D. C."

In testimony whereof, I affix my signature, in the presence of two witnesses.

JOHN H. BRUHN.
